UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A TUMBLER OR SIMILAR ARTICLE.

47,527.

Specification for Design.

Patented June 29, 1915.

Application filed March 12, 1914. Serial No. 824,325. Term of patent 14 years.

To all whom it may concern:

Be it known that I, ANDREW J. SANFORD, a citizen of the United States, residing at Newark, Ohio, have invented a new, original, and ornamental Design for a Tumbler or Similar Article, of which the following is a specification, reference being had to the accompanying drawing, forming part thereof.

Figure 1 is a plan of a tumbler illustrating my new design. Fig. 2 a bottom view, and Fig. 3 a horizontal sectional view taken on the line 3—3 of Fig. 1, looking in the direction of the arrows.

The characteristic feature of the design is the double contrasting aspect of the upper and lower portions of the tumbler. The upper portion has a smooth, cylindrical ex-

terior backed up by a series of convex flutings or panels, which are relatively small; while the lower portion has an exterior composed of a series of concave panels which are relatively large and are backed up by the convex panels above referred to. The convex flutings or panels are the only feature that is common to both the upper and lower portions.

I claim:

The ornamental design for a tumbler or similar article, substantially as shown and described.

ANDREW J. SANFORD.
